UNITED STATES PATENT OFFICE.

WILL H. VAN GUILDER, OF NEW ROCHELLE, NEW YORK, ASSIGNOR TO VAN GUILDER DOUBLE WALL CO., INC., OF ROCHESTER, NEW YORK, A CORPORATION OF NEW YORK.

MOLDING-MACHINE.

1,245,588.

Specification of Letters Patent.

Patented Nov. 6, 1917.

Application filed June 14, 1916. Serial No. 103,666.

To all whom it may concern:

Be it known that I, WILL H. VAN GUILDER, a citizen of the United States, and resident of New Rochelle, in the county of 5 Westchester and State of New York, have invented certain new and useful Improvements in Molding-Machines, of which the following is a specification.

The present invention relates to molding machines and more particularly to the type employed for building concrete walls *in situ*, an object of this invention being to provide a construction which has a maximum adjustability in order that it may be 10 used in the greatest variety of places with the fewest number of parts.

To this and other ends, the invention consists of certain parts and combinations of parts all of which will be hereinafter described, the novel features being pointed out 15 in the appended claims.

In the drawings:—

Figure 1 is an end view of a machine constructed in accordance with the present invention;

Figs. 2 and 3 are sections, respectively, on the lines *a—a* and *b—b* of Fig. 1;

Fig. 4 is a plan view of two machines connected for forming a corner;

Fig. 5 is a view in elevation of the two machines shown in Fig. 4;

Fig. 6 is a plan view of three machines connected together to form two corners and, in addition, to form a wall in close proximity 30 to a window frame;

Fig. 7 is a detailed view of one of the clamps for securing a mold wall to its frame;

Fig. 8 is a perspective view of a machine formed from two frames to produce straight wall work;

Fig. 9 is a sectional view showing the manner in which the core of Fig. 8 connects with the two frames; and

Fig. 10 is a perspective view of the core shown in Fig. 8.

Fig. 11 is a perspective view of a locking plate.

Referring more particularly to the drawings, 1 indicates the mold walls which are preferably in the form of sheet metal plates. For supporting these walls one or more frames are employed. In this instance, each frame comprises two upright members 2 having laterally-turned ends 3 at their up-

per ends secured by bolts 4 to two slide bars 5 and 6, each of said bars having a plurality of openings 7 for the passage of the bolts 4, whereby the uprights may be positioned at different distances apart to adapt the machine to walls of different thicknesses. The bars or slides 5 and 6 are arranged one above the other and are connected by vertical bolts 8 which operate in slots 9 to permit the sliding movement. Movement between the 65 slides may be effected in any suitable means as, for instance, by a lever 10 pivoted at 11 to the lower slide bar and having a link 12 pivoted thereto at 13 and to the upper slide bar at 14, thereby forming a toggle which, 70 when broken, moves the bars in one direction and when straightened moves the bars in the other direction.

The mold walls 1 are mounted on the frame uprights 2 so as to be adjusted longitudinally in order that said plates may be projected different distances from both sides of the frame. Any suitable means may be employed for securing the plates in position, but in this instance the lower ends of the 80 uprights are formed with hooks 15 which are flush with the inner faces of the uprights and receive the lower edges of the mold walls 1, said edges being deflected outwardly at 16 in order to facilitate the positioning the mold upon a completed portion 85 of a wall of a building. The upper edge of each mold wall may be held to its upright 2 by a clamping collar 17 which surrounds the upright and has a lip 18 overhanging 90 the wall; a set screw 19 on the collar co-operating with the upright to hold the collar against movement.

In Figs. 4 and 5, two machines are shown connected together for the purpose of building a corner. In this instance, each machine has one of its walls 1 projected at one side of the frame beyond the other, and this projected wall abuts the projected wall on the other machine at the same time that the 100 other two walls of the machines are brought into abutment. To lock the two walls at the outer edge of the corner of the machine, each of said walls is provided preferably with two alined eyes 20 on its outer face 105 and within these eyes, projections 21 on a connecting or locking member 22 are received, the locking member having two pairs of alined projections, one pair being longer than the other so that one side of the con- 110

nection may be attached before the other. A hand piece 23 is provided on the connection by which the latter may be manipulated.

With the purpose in view of forming an air space in the building wall, constructed from the adjustment shown in Figs. 4 and 5, a core 24 is provided which conforms to the angle of the corner and preferably has a supporting plate 25 at opposite ends which rest upon seats 26 formed on one side of two core-supporting members 27, the latter being secured by bolts 28 to the slide bars 5 and 6. To prevent the cement working between these supporting members 27, the latter are provided with overlapping plates 29 which close the space between the members on one side thereof.

In the adjustment shown in Fig. 6, three molding machines are connected to form two adjacent corners as well as to hug closely an adjacent window frame. In this arrangement instead of the side edges of two mold walls being connected, a side edge of one mold wall is connected to another mold wall at a point removed from the side edge of the latter wall. To permit this connection, each mold wall 1 may have two horizontal or longitudinally-extending series of openings 30 which are larger at one end than at the other. These openings are adapted to be brought opposite the eyes 20 on an adjacent wall in order that aligned pintles 31 which are carried by lateral projections 32 on a locking plate 33 may be introduced with their projections 32 through the openings 30 to engage within the eyes, the projections 32 being enlarged at their ends so that when the narrow portions of the projections enter the narrow portions of the slots 30, the locking bar will be held against movement and will hold a plate 1 against one end of another plate.

In the adjustment shown in Fig. 6, a core member 24^a is provided with supporting plates 25^a, the latter projecting from one end of the core and having downwardly-turned portions 25^b on opposite sides, in order that the supporting member 25^a may rest upon two shoulders or seats 26^a formed by the upper edges of two plate extensions 27^a on supports 27. Between two of the plates 1 a window frame X is received, a core 24^b being interposed between the frame X and the adjacent molding machine frame. At both of the corners formed by this adjustment, two upright angle bars 34 are arranged, said bars being set in a vertical position to define the position of the molding machine as each portion of the wall is built upwardly along the angle bars. If desired, clamps 35 may secure the plates 1 to the angle bars. This bar 34 may also be used in connection with the adjustment shown in Fig. 4.

In the adjustment shown in Fig. 8, two

frames are connected to the walls 1, each frame being connected to both walls near one end of each. A core member 24^c with supporting plates 25^c having flanges 25^b is supported on the seats 26^c. It is apparent that the length of this core, as well as the length of the plates 1, may be varied to make machines of different lengths. This adjustment is designed for making a straight wall with an air space. 75

In using the machine, the two walls 1 are supported on suitable cross pieces such as sheet metal strips which lie within the recesses 36 in the lower edges of the plates 1. After the side walls 1 have been positioned, the core is introduced in place and supported as described, provided that it is desired to build a wall with an air space. If a solid wall is to be built, the core supports 27 are removed. The machine is filled with the cement which is then tamped, after which the machine is immediately removed from the wall, the core piece being first withdrawn, when the walls 1 may be separated by moving the operating lever 10. 90

This invention permits the formation of corners from the walls of the molds without the provision of any extensions on said walls. The walls are longitudinally adjustable on their supporting frames so that they may be projected different distances beyond the frame and in this way may form corners of any angles. This adjustment also permits the machine to hug closely a window or door frame and at the same time 100 the building of straight walls is possible. 95

Certain features herein shown are claimed broadly in an application filed by me on the 13th day of June, 1916, Serial No. 103,442. What I claim as my invention and desire to secure by Letters Patent is:—

1. In combination with a pair of mold walls, a connecting frame having a pair of uprights adjustable relatively to each other and each carrying means for gripping one of said walls at different points along the length of the latter. 110

2. In combination with a pair of mold walls, a connecting frame having a pair of uprights adjustable relatively to each other and provided with seats engaging the lower edges of the walls, and clamps adjustable on said uprights to engage the upper edges of the walls. 115

3. In combination with a pair of mold walls, a connecting frame having a pair of uprights adjustable relatively to each other and each provided with an upwardly-turned lip at its lower end engaging the lower edge of a wall, and a clamping collar surrounding each upright and having a lip engaging the upper edge of a mold wall. 120

4. The combination of two molding machines each of which embodies a frame and two longitudinally adjustable walls, each 130

- provided with alined eyes at opposite ends, and each provided with two longitudinal series of openings, with a locking member having two projections each having a pintle, the projections extending through openings in the two series of one of the walls of one machine and the pintles engaging in the alined eyes on an end of a wall on the other machine.
- 10 5. The combination with a frame, of two mold walls adjustable longitudinally thereon, each wall having alined eyes at opposite ends and each wall also having two series of longitudinally extending openings.
- 15 6. The combination with a frame, of two mold walls adjustable longitudinally thereon to project different distances from either side of the machine, and having alined eyes at opposite ends.
- 20 7. A frame for molding machines comprising two uprights, connecting means between the upper ends of the uprights, means for adjustably securing mold walls to the uprights, and core supporting means depending from the connecting means between the uprights and having seats on opposite sides thereof.
- 25 8. In combination with a pair of mold walls, a connecting frame between the mold walls on which said walls are relatively adjustable in the direction of their lengths, and core supporting means depending from
- said frame between the walls and having means on opposite sides thereof for supporting an end of each of two cores.
9. A mold wall having two alined eyes projecting from opposite sides, and two series of openings extending longitudinally thereof between the eyes, the openings of the two series being arranged so that each one in one series is vertically above another opening in the other series.
10. A mold comprising two relatively shiftable frames each formed of two uprights, two mold walls detachably secured to the uprights, core supporting means depending from the frame between the uprights and a core detachably engaging said core supporting means of the two frames at its ends.
11. The combination with a frame having two uprights, mold walls supported on said uprights, two core supporting devices depending from the frame between the uprights, and a core having a supporting device at one end resting on the two supporting devices on the frame and having downwardly turned portions engaging the outer faces of said two devices.
12. A molding machine comprising two side walls having their lower edges deflected outwardly and provided with notches, the notches on the two walls being opposite.

WILL H. VAN GUILDER.
